UNITED STATES PATENT OFFICE.

GEORGE P. BUMP, OF LA CROSSE, WISCONSIN.

DESIGN FOR A CASING FOR PAPER-FASTENING DEVICES.

46,109.

Specification for Design.

Patented July 21, 1914.

Application filed August 16, 1913. Serial No. 785,162. Term of patent 14 years.

To all whom it may concern:

Be it known that I, GEORGE P. BUMP, a citizen of the United States, residing at La Crosse, Wisconsin, have invented a new, original, and ornamental Design for Casings for Paper-Fastening Devices, of which the following is a specification, reference being had to the accompanying drawing, forming a part thereof.

The figure is a perspective view of a cas-

ing for paper fastening devices showing my new design.

I claim:

The ornamental design for a casing for paper fastening devices as shown.

GEORGE P. BUMP.
